UNITED STATES PATENT OFFICE.

JOSEPH P. McHUGH, OF NEW YORK, N. Y.

METHOD OF PRODUCING GRILLE OR SCROLL WORK.

SPECIFICATION forming part of Letters Patent No. 544,109, dated August 6, 1895.

Application filed March 20, 1895. Serial No. 542,455. (No model.)

To all whom it may concern:

Be it known that I, JOSEPH P. McHUGH, a citizen of the United States, residing at No. 3 West Forty-second street, in the city, county, 5 and State of New York, have invented new and useful Improvements in the Methods of Producing Grille or Scroll Work, of which the following is a specification.

My invention relates to the production of 10 ornamental grille or scroll work, such as may be used in house decoration or employed for panels, screens, and similar articles.

My invention, broadly stated, consists in combining with a base so constructed that it 15 will not warp under variations of temperature and through which a specified open-work pattern has been formed, a plastic ornamentation applied to one or both surfaces of the base and corresponding in general design 20 to the pattern formed in the base and having a surface ornamentation in appearance simulating carving.

To carry my invention into effect, I proceed as follows: I first prepare a base made of 25 three layers of wood glued together with their grains crossed, and upon this base a design is traced and cut out with a jig-saw, or by any other suitable means such as is commonly employed in making ordinary surface scroll-work. Subsequently I apply to one or both 30 surfaces of the base a plastic ornament which corresponds in general outline with that of the design formed by the remaining portion of the base, and having its exterior surface 35 so molded to give it the appearance of a carved surface in relief.

The composition which may be employed for the plastic ornamentation may be that 40 commonly used for making ornaments by manufacturers of picture or mirror frames, and may be attached to the backing by means of glue or cement, or it may be mechanically secured thereto. The general effect of the grille or scroll work when completed and colored is that of an extremely well-executed 45 piece of wood-carving. I am thus enabled to obtain a decorative effect corresponding to that of fine wood-carving at an extremely small cost for production.

50 The accompanying drawings will serve to further illustrate my invention as carried into effect.

Figure 1 is a front view of a grille or scroll work made according to my invention. Fig. 2 is a vertical section through the base or 55 body portion. Fig. 3 is a front view illustrating the manner of making up the base and also showing a design traced upon the base and formed through the base, that at the right of the figure being cut out and ready 60 for the application of the plastic ornament. Fig. 4 is a front view of a plastic ornament corresponding to the design upon the base and ready to be applied. Figs. 5 and 6 are vertical sections showing, respectively, the 65 base with one or two decorative surfaces.

Similar letters of reference indicate like parts.

A represents the base, which is composed of thin layers of wood *a b c*, which are glued 70 together so that their grains cross, as shown in Fig. 3.

B represents the plastic ornament, which may be given any general and surface design and applied to either one or both 75 surfaces of the base.

The perforations or openings through the base are indicated by C.

Instead of cutting out the design upon the base prior to the application of the plastic 80 ornament, I may first apply the ornament and then cut out all of that portion of the base not covered by the ornament.

I wish it understood that I do not claim as my invention the method of forming the base 85 of three layers of wood herein described. Neither do I claim to be the first to apply a plastic ornament to a base which will not warp.

What I do claim as my invention is—

1. The improvement in the method of producing grille or scroll work described, which consists in producing upon a suitable base, any required open work design, and subsequently applying to one or both surfaces of 95 said base, a plastic open work ornament corresponding in general outline to said design.
2. In a grille or scroll work, the combination of a base with an open work design formed therein, and a plastic open work ornamentation corresponding in general outline to the design of the base and applied to one or both surfaces of said base.
3. As a new article of manufacture, a screen,

grille or decorative panel, comprising an open work base formed of three layers of wood with the grains crossed, and having an exterior surface or surfaces formed of a decorative plastic material corresponding in general outline to the design of the open work base.

In testimony whereof I affix my signature in the presence of two witnesses.

JOSEPH P. McHUGH.
